UNITED STATES PATENT OFFICE.

FRANK L. COVERT, OF KIRKWOOD, NEW YORK.

DIRIGIBLE AIRSHIP.

Application filed December 13, 1924. Serial No. 755,751.

To all whom it may concern:

Be it known that I, FRANK L. COVERT, a citizen of the United States, residing at Kirkwood, in the county of Broome and State of New York, have invented certain new and useful Improvements in a Dirigible Airship, of which the following is a specification.

This invention has a general reference to air crafts but has more specific reference to a giant dirigible air ship which I have devised especially for use in time of war, although the invention will be found useful in times of peace also.

It is my primary aim to construct an airship of this class which is adaptable for forming a landing for aeroplanes while afloat. It is my idea to construct an airship with a specially designed landing whereby the planes may either take off or land safely, a single air ship being sufficient for conveying a number of planes to a point of advantage in time of battle.

An important feature of the invention is to so construct the air ship that the landing will be in the form of a runway, the same being disposed at the top of the ship and being properly centered so that the same will not be overbalanced during the ascension or descension of the smaller planes.

It is also within my conception to construct the ship to facilitate loading and unloading of passengers, aviators and the like. It therefore follows that it is a feature to equip the air ship with an elevator in communication with the landing.

There are other features and advantages present in the invention and these will become apparent from the following description.

In the drawing:

Figure 1 represents a side elevation of an air ship constructed in accordance with the present invention.

Figure 2 is a top plan view thereof.

Figure 3 is an enlarged transverse section taken on the line 3-3 of Figure 1.

Figure 4 is a detail view showing the elevator, its shaft and the runway.

In the drawing, the airship is generally designated by the numeral 1. In adapting the same to accomplish the end sought, it is provided at the center of its top with a runway 2 having a properly supported platform or bottom 3 constituting a landing for aeroplanes 4. It is to be observed from

Figure 2 that the runway gradually increases in width and decreases in depth from front and toward the rear end. This facilitates both ascension and descension. I propose to have the runway extending for substantially the full length of the ship. Particular emphasis is to be laid on the fact that the use of a runway is exceedingly important in that it serves to guard against possible overbalancing of the ship. For instance, if the landing were on the top of the craft, disastrous result might be encountered. Obviously, by having the sunken landing and disposing the same at the exact center, there is little doubt that disastrous effects would be suffered.

At the forward end the runway communicates with a vertical elevator shaft 5 in which a suitable car 6 is movable. The car may be of a size to accommodate a plane or it may be constructed for accommodating passengers only, whichever plan is found most advantageous for loading and unloading passengers. If the first plan is followed, the planes might be lowered and stored in convenient compartments formed within the ship. As seen more clearly in Figure 4, the elevator shaft is in communication with the runway and in fact extends above it, a suitable closure 7 being provided for use at this end. At its lower end, the shaft is in communication with suitably constructed passenger containing compartments 8.

In addition to the parts so far described, I have shown passenger cabins 9, motors 10, gas inflated bags 11, suitable bracing, etc. I also contemplate employing ladder-ways 12 of any suitable configuration and preferably leading from the bottom of the craft to escape openings in the top. These may well serve to permit access to disappearing machine guns 13 distributed along the top of the ship. It may also be advantageous to have additional guns 14 located in the aforesaid runways.

While I have shown and described the invention as being particularly adaptable for use in war time, I wish it to be understood that it will be quite advantageous for use in times of peace. For instance, while the air ship is in flight, passenger planes may ascend from or alight on the landing for loading and unloading passengers while the ship is in flight.

I wish it to be understood that while I have shown and described a specific em-

bodiment of the invention, changes such as fall within the field of invention claimed may be resorted to if desired.

Having thus described the invention, what

5 I claim is:—

1. An airship formed at the center of its top with a depression forming a runway and a landing for aeroplanes, and an elevator leading from the interior of the ship

10 to said runway.

2. An airship provided in its top with a longitudinal centrally disposed depression forming a runway and a landing for aeroplanes, said depression increasing in width and decreasing in depth at its rear end, a ¹⁵ vertical elevator shaft in the ship in communication with said runway, and an elevator adapted to travel in said shaft.

In testimony whereof I affix my signature.

FRANK L. COVERT.
